UNITED STATES PATENT OFFICE.

WILLIAM NELSON, OF NEW YORK, N. Y., ASSIGNOR, BY MESNE ASSIGNMENTS, TO
CONSOLIDATED AMERICAN FASTENER COMPANIES, INC., OF NEW YORK, N. Y.,
A CORPORATION OF NEW YORK.

MACHINE FOR MAKING THE STUD MEMBERS OF SNAP-BUTTONS.

1,358,773.

Specification of Letters Patent. Patented Nov. 16, 1920.

Application filed October 6, 1916. Serial No. 124,119.

To all whom it may concern:

Be it known that I, WILLIAM NELSON, a citizen of the United States, residing in New York, county and State of New York, have 5 invented certain new and useful Improvements in Machines for Making the Stud Members of Snap-Buttons, of which the following is a specification.

This invention relates to the manufacture 10 of one of the parts of the well known snap fastener or press button which comprises two members, a stud and a socket.

In a co-pending application for patent filed by me September 22, 1916, Serial No. 15 121,622 a machine is shown, described and claimed for making the stud member in which the stock, in the form of a metal strip or ribbon, is fed step by step between a series of sets of upper and lower dies which draw 20 metal from the stock, gradually reduce the metal thus drawn to proper size for the stud post, then form a head on the post, then blank out the stud from the stock and turn down its peripheral edge, and then transfer 25 the flanged stud to another set of dies which curl under or double the edge of the base portion of the stock.

My improved machine is similar in many respects to that above referred to but differs 30 therefrom in that whereas in the before-mentioned machine the stud was separated from the stock before the operation which curls or doubles the edge of the base and finishes the stud, according to my present 35 invention the stud has the edge of its base portion flanged for the curling operation before it is separated from the stock.

Experience has demonstrated that the step 40 of transferring the studs from the blanking- out to the curling dies is a delicate operation and required great care but this difficulty has been entirely overcome by my present improvements.

In the accompanying drawings:

45 Figure 1 is a side elevation of a stud forming machine embodying my improvements.

Fig. 2 is a plan view of the stock showing the manner in which the dies operate thereon to produce the stud.

50 Fig. 3 shows a vertical longitudinal section through the stock illustrated in Fig. 2.

The remaining figures of the drawings are on an enlarged scale.

Fig. 4 is a bottom plan view of the upper

dies for blanking out the studs and for curling the edges of the stud bases.

Fig. 5 is a top plan view of the lower dies for blanking out the studs and for curling the edges of their bases.

This drawing also shows the devices employed for separating the completed studs from the stock and also a portion of the stock feed mechanism.

Fig. 6 illustrates in vertical section the dies and feed mechanism shown in Figs. 4 and 5.

Fig. 7 is a detail view in vertical section of the curling dies and the slide for ejecting the completed studs from the curling dies.

In Fig. 7 the upper die is in its elevated position and the ejecting slide is in the position it assumes after the stud has been ejected.

Fig. 8 is a view similar to Fig. 7 but shows the upper die lowered and the ejecting slide in its withdrawn position.

The dies and the mechanism associated therewith may be supported in any suitable way and operated by mechanism of the kind shown in my before-mentioned application for patent.

The stock, in the form of a metal strip or ribbon X, is passed through a guide A and between the upper and lower dies and then to a feeder B which is operated to pull the stock through the machine step by step between the dies.

The upper dies and punches for forming the studs are carried by an upper die carrier D and the corresponding lower dies and punches are carried by the bed-plate E. The upper die carrier is raised and lowered by any suitable mechanism and is guided by posts F rising from the bed-plate and entering sockets F' in the upper die carrier.

The stock is first operated upon by upper and lower dies G, G' to draw the metal in such manner as to gradually form a projection on the stock which is subsequently shaped to form the headed post of the stud 100 in the manner described in my application for patent before mentioned and as the devices for forming the heads on the stud posts form no part of the invention herein claimed they are not illustrated in the drawings.

After a projection of the proper size is formed the stock is advanced until the projection arrives between the upper and lower

punches H , H' which pierce that part of the stock which is to form the base of the stud and thus form holes for the thread by means of which the stud is secured to a garment or 5 to a fabric.

By reference to Figs. 2 and 3 the manner in which the stock is treated by the dies will be better understood. The parts 1, 2, 3, 4, 5 and 6 are formed successively by the 10 dies G , G' . 7 indicates where the thread holes are formed. 8 and 10 indicate parts not operated upon by the dies, while 9 indicates where the initials of the manufacturer are applied. At the point 11 the 15 metal is drawn or bent upward to form a downwardly extending flange Y on the stud blank without separating the blank from the stock.

The dies for embossing the initials of the 20 manufacturer on the stud blanks are indicated at J , J' .

The dies for forming the flanges on the stud blanks are indicated at K , K' . These dies are more clearly shown in Fig. 6. The 25 upper die K comprises a bar k having a central bore k' and a recessed end k^2 . The bar k is attached to a block k^3 secured to the upper die carrier D . K^2 indicates a spring-pressed stripper for the upper die. The 30 lower die K' comprises a bar k^4 mounted in a block k^5 supported on the bed plate E . K^4 indicates a spring-pressed stripper for the lower die. As the stock is fed between the dies at the proper time the metal is 35 pressed by the dies K , K' in such manner as to form a flange Y on the stud blank. This is indicated in Fig. 3 at 11.

After the stud blank has been flanged the stock is moved forward two steps and the 40 blank comes between the dies L , L' which cut it from the stock. The upper die L comprises a cylindrical hollow bar l attached to the die carrier D and this block incloses a plunger die l' having a central 45 bore l^2 and a recessed end l^3 . The walls of the recess are so formed as to provide a thin edge l^4 . A strong spring l^5 pushes the plunger downward.

The lower die L' comprises a bar l^6 connected with a block l^7 resting on the bed plate E and extending through a spring-pressed stripper block l^8 . The bar l^6 is formed with a projection l^9 adapted to enter the recess l^3 . When the blank arrives 55 at the dies L , L' the upper die descends and the stock is cut as indicated at 13 in Figs. 2 and 3. The blanking dies are not positive in their action as they are spring-pressed. The cutting is actually performed by the 60 edge z of block l . As soon as the die carrier D moves upward the strong spring l^5 , above the die l' , moves the latter back to its normal position and the blanked out stud is separated from the upper dies, the stud being still held in position in the stock.

After the stud has been thus blanked out in the stock the latter moves forward two steps to the curling dies M , M' . The upper die M comprises a hollow bar m within which is adapted to slide a rod m' against 70 the upper end of which bears a spring m^2 housed in a recess in the die carrier D . The bar m is held by a block m^3 attached to the die carrier and the lower end of this bar extends through a spring-pressed stripper 75 M^2 . The lower end of the bar m is recessed as indicated at m^4 and it is also recessed on its side at m^5 in such manner as to co-operate with the lower die M' to curl or double the flange Y on the blank. The lower 80 die M' is set in a block m^6 resting on another block m^7 supported by the bed plate E . Within the block m^7 is an anvil m^8 which is recessed at m^9 in such manner as to co-operate with the recessed end of the bar 85 m to curl the flange on the stud blank. The recesses indicated at x in Fig. 6 accommodate the studs as they are moved from one set of dies to another, to prevent crushing of the studs when they are in positions between dies upon lowering of the carrier D .

When the die carrier D descends the top of the post of the stud is engaged by the rod m' and the stud is forced into the lower curling die M' . Continued downward 95 movement causes the head of the post to enter the lower end of the bore of bar m , the edges of the base of the stud resting upon the inclined walls of the lower curling die M' . It will be understood that the 100 rod m' moves inwardly against the pressure of the spring m^2 during this operation. When the die carrier moves farther downward, the lower end of the hollow bar m engages the upper face of the stud base and 105 forces the latter downward. By reason of the inclination of the walls of the die M' the pressure of the bar m upon the stud base will cause the flange depending from the edge to move inwardly just prior to the time the base reaches the anvil m^8 . With the stud resting upon the anvil downward movement of the hollow bar m will cause the now inwardly inclined depending flange to be curled upon the under face of the stud 115 base. The recesses m^4 and m^5 in the curling dies prevent mashing or distorting the base or its curled flange.

It will be observed that the stud blank remains in the stock while passing from the 120 blanking out dies to the curling dies but during the curling operation the stud is separated from the stock and is transferred to a lower level in front of an ejector slide N which operates just above the anvil m^8 . 125 The slide N transfers the completed stud to a position over a hole O in the block m^7 through which the stud falls into a hole O' in the bed plate, from which it passes to a suitable receptacle.

The slide N is bifurcated at its front end and is reciprocated in a guide formed between the blocks m^6 and m^7 . At its end the slide carries a roller n operating in a 5 slot p in a cam plate P attached to the upper die carrier D. When the upper die carrier descends the slide is withdrawn, the curling operation is performed and when the dies rise the slide moves forward and the stud is 10 dropped through the holes O, O'. It will be understood that the strippers hereinbefore referred to operate in the usual way.

After leaving the dies M, M' the stock passes through a guide Q provided with 15 a spring q and then it passes to the stock feed mechanism B. This mechanism comprises a lower lever b pivoted at b' to a block e on the bed plate E and formed with a bifurcated laterally projecting arm b^2 having a jaw b^3 which co-operates with a jaw b^4 on the upper lever B', which is pivoted at b^5 to the lever b. The lever B' carries a roller b⁶ operating in a slot s in a cam plate S attached to the upper die carrier. A set 20 screw T carried by a bar t is employed for adjusting and regulating the feed. U indicates spring brakes for restraining the movement of the lever b thus insuring the proper movement of the lever B'. W indicates guide pins for the dies.

It will thus be seen that much of the mechanism herein shown and described is similar to the mechanism shown in my application for patent before mentioned, but 35 it will also be observed that according to my present invention the stud blank is retained in the stock until after the curling operation is accomplished on the flanged blank and that the stud is not separated entirely from the stock until all the operations 40 have been performed thereon.

I claim as my invention:

1. A stud making machine comprising means for feeding the stock and a series of 45 sets of upper and lower dies, the first set being provided with means for forming a stud post in the stock, the second set having devices for forming a flange therein surrounding the post and thus defining the base 50 of the stud without separating the flange from the stock, a third set of dies having means for cutting the stock surrounding the flange without removing the stud blank from the stock, and a fourth set of dies having 55 devices for doubling the peripheral edge of the base portion of the stud.

2. A stud making machine comprising means for feeding the stock intermittently and a series of sets of upper and lower 60 dies, the first set being provided with means for forming a stud post in the stock, the

second set having devices for forming a flange therein surrounding the post and thus defining the base of the stud, another set of dies being provided with means for cutting the stock surrounding the flange without removing the blank from its position in the stock, and another set of dies being provided with devices for curling or doubling the peripheral edge of the stud base 65 and for separating the stud thus formed from the stock.

3. In a stud making machine, means for operating upon the stock to provide a post thereon, means for forming a flange on the 75 stock surrounding the post and disposed at an angle to the stock, means for cutting the lower end of the flange from the stock, and means for curling the said flange.

4. In a stud making machine, means for 80 operating upon the stock to provide a post thereon, means for successively forming a flange upon the stock surrounding the post and for cutting the flange from the stock, and means for curling the said flange.

5. In a stud making machine, means for operating upon the stock to provide a post thereon, means for forming an angular flange upon the stock surrounding the post and thus defining the base of the stud, means 90 for cutting the flange from the stock, means for changing the inclination of the flange, and means for curling the said flange upon the stud base.

6. In combination with the subject matter of claim 5, and means for removing the stud from the curling means.

7. In a stud making machine, means for operating upon the stock to provide a post thereon, means for forming an angularly disposed flange upon the stock surrounding the post and thus defining the base of the stud, means for cutting the flange from the stock, means for changing the inclination of the flange, means for curling the flange upon the 100 stud base, and an ejector for moving the stud after the flange curling operation.

8. In a stud making machine, means for operating upon the stock to provide an 105 standing post thereon, means for forming an angularly disposed flange upon the stock surrounding the post, means for cutting the flange from the stock, and means for curling the flange upon the under side of the stud base.

In testimony whereof, I have hereunto 110 subscribed my name.

WILLIAM NELSON.
